(57) **CLAIM**

The ornamental design for a shaving razor cartridge container as shown and described.

DESCRIPTION

FIG. 1 is a top perspective view of a design of a shaving razor cartridge container showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a second top perspective view thereof; and,

FIG. 9 is a bottom perspective view thereof.

The dash lines shown illustrate portions of the shaving razor cartridge container and form no part of the claimed design. The dot-dash lines form a boundary to the claimed design and form no part thereof.

1 Claim, 7 Drawing Sheets
